REVERSIBLE ENGINE CONTROL APPARATUS

Ralph C. Brooks, Turtle Creek, Pa., assignor to
Westinghouse Air Brake Company, a corpora-
tion of Pennsylvania

Application October 7, 1949, Serial No. 120,121

9 Claims. (Cl. 60—16)

1

This invention relates to reversible engine control equipment and more particularly to control apparatus adjustable in accordance with the direction of rotation of a reversible engine for controlling the supply of fuel to same.

In certain fluid pressure reversible engine control systems, a directional interlock valve device is employed in reversing the engine to effect holding of the fuel supply to the engine cut-off until the engine is rotating in its proper direction in accord with the position of an operator's control lever. Such an interlock device usually comprises a retractable shoe which is adapted to be actuated into frictional engagement with a rotary part of the engine, such as the crank shaft, to be biased in one or another direction according to rotation of the crank shaft for conditioning a fuel control device accordingly.

Heretofore, in the control systems employing the above directional interlock valve device, if, in reversing the engine, the operator moved the operator's control lever to a position to call for termination of the supply of starting air and for the supply of fuel to the engine at a time when the engine crank shaft has merely begun to turn in its new or reverse direction; such termination would be effected, the directional interlock device would assume its reverse position for allowing fuel to be supplied to the engine while the shoe of the interlock device would move to its retracted position away from the engine crank shaft. Under these conditions, if the engine "rocked" so that its crank shaft momentarily started to turn back in its original direction of rotation there was danger that the fuel supplied to the engine might fire and cause unintended running of the engine in its original direction of operation, and with the directional interlock shoe retracted, the directional interlock device would be helpless to prevent such unintended running, so that damage to the engine and equipment might result before the operator could cut off the fuel supply through manipulation of the operator's lever.

It is a principal object of the present invention to provide reversible engine control apparatus comprising a directional interlock device which will operate automatically to prevent the above described unintended running of the engine should "rock" occur during engine reversal.

Other objects and advantages will become apparent from the following detailed description of the invention.

In the accompanying drawing, the single figure is a schematic view of a control system embodying the invention.

Description

The reversible engine (not shown) may comprise the usual crank shaft 1, only a portion of which is shown in the drawing. The crank shaft 1 may be operably connected to the pistons (not

2

shown) of the engine and operatively connected to a device to be operated (not shown). The engine may further comprise a fuel control shaft 3 operatively connected to fuel control valve means (not shown) for regulating the quantity of fuel supply to the engine by way of fuel injection nozzles or the like (not shown). The control shaft 3 is secured for turning movement with a fuel control lever 4 which may be disposed outside the engine. The lever 4 is arranged to be moved to a "Fuel Off" position, indicated by a dot and dash line so legended in the drawing, in which position the fuel control valve means is conditioned to shut off the supply of fuel to the engine cylinders. By a counterclockwise turning movement of lever 4, as viewed in the drawing, from its "Fuel Off" to a "Full Fuel" position, the fuel may be increased up to a maximum amount corresponding to the latter position. The fuel control lever 4, when not otherwise urged to its "Fuel Off" position and when the engine is turning over will be caused to assume positions out of "Fuel Off" toward "Full Fuel" according to dictates of such as a speed governor device (not shown).

The control apparatus embodying the invention may comprise a starting air control valve device 6, a fuel cut-off cylinder device 5 for effecting movement of the fuel control lever 4 to its "Fuel Off" position, as in stopping the engine for reversal, a directional interlock device 7 for controlling operation of the fuel cut-off cylinder device 5, an operator's control device 8 for controlling the operation of the directional interlock device 7, and, according to the invention, a choke 9 and check valve 10 interposed between the operator's control valve device 8 and the directional interlock valve device 7.

In addition, the control apparatus comprises a fluid pressure reservoir 11 adapted to receive fluid under pressure from such as a compressor (not shown) as a source of supply of working medium for the control system as well as a source of supply of starting air for the engine. A reducing valve 12 is provided to transform reservoir pressure to a pressure suitable for operation of the control system.

The fuel cut-off cylinder device 5, for sake of illustration, may comprise a hollow cylindrical casing 30 having a fuel cut-off piston 31 slidably disposed therein. Piston 31 is arranged to be exposed on its one face to pressure of fluid in a pressure chamber 32 and on its opposite face to the force of a compression spring 33 disposed in an atmospheric chamber 34. A stop rod 35, attached to piston 31, extends outwardly through the casing 30 for engagement with the fuel control lever 4. When fluid under pressure is supplied to the pressure chamber 32, the piston 31 will be caused to assume the position in which it is shown in the drawing, with the stop rod 35 in engagement with the fuel control lever 4 and

3

holding same in its "Fuel Off" position. Upon release of fluid under pressure from the pressure chamber 32, the piston 31 will be moved by spring 33 in the direction of chamber 32 to a release position defined by contact with a shoulder 36, in which position the stop rod 35 will be retracted away from the fuel control lever 4 to allow same to be moved in the direction of a "Full Fuel" position by means of a speed governor device (not shown) or the like for effecting the supply of fuel to the engine.

The starting air valve device 6 may comprise a casing 53 having a diaphragm 54 disposed therein and subject to the pressure of fluid in a diaphragm control chamber 55 on one side and to the pressure of fluid in a chamber 56 on its opposite side, which latter chamber is open to atmosphere via a port 57 in the casing. Also formed in the casing are chambers 58, 59 and 60, chamber 58 being separated from chamber 56 by a partition 61 and from chamber 59 by a partition 62. A partition 63 separates chambers 59, 60. A valve 64 is disposed in chamber 60 for controlling communication between said chamber and the chamber 59. Valve 64 may be secured to a fluted stem 65 slidably mounted in a suitable bore extending through the partition 63, a seat being formed at the end of said bore to accommodate said valve. A bias spring 68 is disposed in chamber 60, arranged to urge the valve 64 in the direction of its seat. A valve 69, similar to valve 64, is disposed in chamber 58 for controlling communication between said chamber 58 and the chamber 59. For slidably guiding the valve 69, a fluted stem 70 is provided which is slidably disposed in a suitable bore opening through partition 62. A valve seat is formed in partition 62 encircling one end of the last mentioned bore for accommodating the valve 69. Stems 65, 70 project into and meet in the chamber 59 in such a manner that action of bias spring 68 on valve 64, in urging same in the direction of its seat, at the same time, through said stems, urges valve 69 in a direction away from its respective seat. If valve 69 is seated, valve 64, consequently, will be unseated. Valve 69 is operably connected to the diaphragm 54 by means of a rod or stem 73 extending therebetween through a bore in partition 61 in which said rod is slidably disposed. A control spring 76 is provided in chamber 56, arranged to oppose deflection of the diaphragm 54 in the direction of chamber 56 as caused by pressure of fluid in chamber 55 for determining the degree of said pressure necessary to effect operation of valves 64, 69.

In operation, the device 6 will respond to a certain pressure of fluid in the control chamber 55 to close valve 69 and open valve 64 thereby closing chamber 59 to chamber 58, while at the same time opening said chamber 59 to the chamber 60. Upon a subsequent certain reduction in pressure of fluid in control chamber 55, springs 68 and 76 will close valve 64 and open valve 69 to again connect chamber 59 to chamber 58 and to close said chamber 59 from chamber 60.

In the starting air valve device 6, the chamber 59 is connected to a pipe 75 for conveying starting air to the engine, chamber 60 is connected to the reservoir 11 by a pipe 74, and chamber 58 is open to atmosphere via a port 80.

The directional interlock device 7 in the usual form comprises a casing having two poppet valves 131 and 132 contained in chambers 133 and 134 respectively. The poppet valves 131 and 132 are arranged side by side with parallel extending fluted stems 135 and 136, respectively, which

4

extend into a chamber 137 common to both. The valves 131 and 132 are provided to control communication between the chambers 133 and 134, respectively, and chamber 137. A spring 138 in each of the chambers 133 and 134 acts on the respective valve 131, 132 to urge same toward a closed position, in which position the valve 131 is shown in the drawing.

The valve stems 135 and 136 engage, respectively, two spaced apart operating plungers 139 and 140 which are slidably mounted in the casing and which are provided with stems 141 and 142 extending outwardly through the casing. Two rockable cams 144 and 145, fulcrumed on pins secured to the casing, are provided for actuating the plungers 141 and 142, respectively. These cams may be identical but reversely arranged, and each is operatively connected to the respective plunger 141, 142 through the medium of a follower element 147 rockably mounted on a pin secured in the casing. Each of the cams 144 and 145 is provided with a surface 149, which, when in engagement with the respective element 147, will unseat the respective valve 131 or 132. Adjacent to the surface 149, each cam is provided with a recess 150 which is adapted to receive the respective element 147 to permit movement of the respective plunger 139 or 140 by a spring 151 to a position to permit closure of the respective valve 131 or 132 by the respective spring 138.

The two cams 144 and 145 are operatively connected for movement in unison by a link 152, and since the cams are reversed as above mentioned, movement of the link and cams to the position in which they are shown in the drawing will effect opening of the valve 132 and closure of the valve 131, while movement of said link and cams in an opposite direction to a position in which the surface 149 on the cam 144 engages the respective element 147 will effect opening of the valve 131 and closing of the valve 132.

The directional interlock device 7 further comprises a shoe actuating piston 154 which is operatively connected to the link 152 by means of a piston rod 155, which extends through a non-pressure chamber 156 at one side of said piston. At the opposite side of the piston 154 there is a pressure chamber 157. The opposite or outer end of the piston rod 155 is connected by a pin 159 with a friction shoe 161 which is adapted and arranged for frictional engagement with the outer surface of the crank shaft 1. The piston rod 155 is also operatively connected by means of pin 159 to one end of a link 163, the opposite end of which is operatively connected to the link 152 by means of a pin 163'.

The piston rod 155 is capable of side movement in the non-pressure chamber 156 from the position in which it is shown in the drawing, and 60 which is defined by contact with a surface 164 in the casing, to a position in which said rod engages a surface 165 in the casing. Adjacent to the surface 165, the casing is provided with a pin 166 which is arranged to engage in one of 65 two recesses 167, 168 according to whether or not the piston rod is in the position in which it is shown in the drawing or is in its opposite position engaging the surface 165.

When fluid under pressure is supplied to the 70 pressure chamber 157, in a manner which will be described hereinafter the piston 154 will move the friction shoe 161 into engagement with the engine crank shaft 1, which, if rotating, will bias the rod 155 toward one or the other of surfaces 164 or 165, according to the direction

in which said shaft is turning. At the time of engagement of the shoe 161 with the shaft 1, the link 163 will be disposed away from the pin 166, so that the rod 155 is free for sidewise movement to effect positioning of the cams 144 and 145 accordingly. If, at the time of engagement of the shoe 161 with the shaft 1, said shaft is rotating in one or its "Forward" direction, the rod 155 will be biased to the position in which it is shown in the drawing in leaning engagement with the surface 164, and the cams 144 and 145 therefore will be caused to assume the positions in which they also are shown in the drawing with the valve 131 consequently closed and the valve 132 open. If, conversely, the shaft 1 is rotating in the other or its "Reverse" direction at the time of engagement by the shoe 161, the rod 155 will be caused to assume its opposite position in leaning engagement with the surface 165, thereby effecting shift of the cams 144, 145 to their positions in which the valve 132 is closed and the valve 131 is opened. If, however, at the time that the shoe 161 engages the shaft 1, said shaft is static, the rod 155 will remain in leaning engagement with whichever of the shoulders 164 or 165 it may be in such engagement with at the time. Upon release of fluid under pressure from the chamber 157, a spring 170 will move same in the direction of said chamber to a rest position in which it is shown in the drawing, while the shoe 161 will thereby be moved to a corresponding rest position seated on accommodating shoulders 171 formed in the casing. The link 163 will return into contact with the pin 166 which will project into one or the other of the recesses 167 or 168 to lock the piston rod 155, cams 144, 145 and the valves 131, 132 in the positions which they were caused to assume when the shoe 161 last engaged the shaft 1 when rotating.

In the directional interlock device 7 the chamber 137 is connected via a pipe 180, a shuttle valve 181 and a pipe 182 to the chamber 32 in the fuel cut-off cylinder device 5, the chamber 134 is connected to a "Reverse Control Pipe" 185, the chamber 133 is connected to a "Forward Control Pipe" 186, and according to the invention, the chamber 157 is connected to the outlet side of the choke 9 and check valve 10 by way of a pipe 190 and a branch thereof. The inlet sides of the choke 9 and check valve 10 are connected to branches of a "Start Control Pipe" 202 which has a connection with the chamber 55 in the starting air valve device 6.

The operator's control device 8 may be of the type described in United States Patent No. 2,433,916 issued to H. C. May et al., January 6, 1948, and briefly may comprise an operator's control lever 200 adapted to be moved to various positions within a guide slot 201 for actuating valve means (not shown) comprised therein for selectively establishing pressurization of the "Forward Control Pipe" 186, "Reverse Control Pipe" 185, and a "Start Control Pipe" 202, as well as to effect variation of pressure of fluid in a speed control pipe 203.

In the usual control system, variation in pressure in the speed control pipe 203 is employed to effect a corresponding regulation in the speed setting of the governor device, however, such regulation is not pertinent to the present invention, and description of such variation as effected by the operator's control device 8 has been omitted from the present application.

In operation of the operator's control device 8, 75

only establishment of supply and release of fluid under pressure to and from the control pipes 185, 186, 202 will be considered herein, since only those are pertinent to an understanding of the invention.

When operator's lever 200 is moved to "Stop" position, in which position it is shown in the drawing, the control pipes 185, 186 and 202 are vented to atmosphere.

10 When the operator's lever 200 is moved out of "Stop" position in the slot 201 in the direction tilted "Forward," the "Forward Control Pipe" 186 will be charged with fluid under pressure, while the "Reverse Control Pipe" 185 and the "Start Control Pipe" 202 remain vented.

15 When the operator's lever 200 is moved in slot 201 out of "Stop" position in the opposite direction, that is, in the direction bearing the legend "Reverse," the "Reverse Control Pipe" 185 will be charged with fluid under pressure while the "Forward Control Pipe" 186 remains vented as in "Stop" position.

20 By movement of operator's lever 200 from slot 201 on either the "Forward" or "Reverse" sides 25 of "Stop" position into and out of respective slots 210, 211 to respective "Start" positions, the "Start Control Pipe" 202 will be charged with fluid under pressure and vented, respectively, while the status of the control pipes 186, 185 will 30 remain unaffected by such movement into and out of the "Start" positions.

25 In the usual manner, with the operator's control lever 200 in "Stop" position and the control pipes 185, 186 and 202 vented, the chamber 32 in

35 the fuel cut-off cylinder device 5 will be charged with fluid under pressure supplied thereto by way of pipe 182, shuttle valve 181 and a pipe x which in turn is usually supplied with fluid under pressure by way of a relay valve device (not shown) which responds to venting of both control pipes 185, 186 to effect such supply to the pipe x. When the operator's lever 200 is moved

40 out of "Stop" position in either direction, with one or the other of pipes 185, 186 consequently charged with fluid under pressure, the relay valve device (which is not shown) will vent the pipe x. It will therefore be seen that control of operation, that is, supply and release of fluid under pressure to and from the fuel cut-off cylinder device 5, will be under the control of the directional interlock device 7, via pipe 180, shuttle valve 181, and the pipe 182 when the operator's control lever 200 is out of "Stop" position, as will 45 be true when reversing the engine, for example.

50 55 60 65 70

Operation

Assume that the operator's control lever 200 is positioned in slot 201 at the "Forward" side of "Stop" position intermediate "Full Speed" and "Run and Idle," for example, with the "Forward Control Pipe" 186 consequently charged with fluid under pressure and the "Reverse Control Pipe" and "Start Control Pipe" vented; assume that the engine is running with crank shaft 1 turning in its "Forward" direction; and assume that the directional interlock device 7 is in its corresponding forward position in which it is shown in the drawing with valve 132 unseated, opening pipe 180 to "Reverse Control Pipe" 185, and with the valve 131 seated, closing off the pipe 180 from the "Forward Control Pipe" 186.

75 80 85 90 95

With the "Reverse Control Pipe" 185 vented, the chamber 32 in the fuel cut-off cylinder device 5 also will be vented via pipe 182, shuttle valve 181, pipe 180, the unseated valve 132 in

the directional interlock device 7, and said "Reverse Control Pipe" so that piston 31 in said device 5 will be so positioned that stop rod 35 will be in its retracted position disposed away from the fuel control lever 4, allowing for supply of fuel to the engine assumed to be running forward.

With the "Start Control Pipe" 202 vented, the chamber 157 in the directional interlock valve device 7 will be vented by way of the pipe 190, choke 9, and said "Start Control Pipe" as also will be the chamber 55 in the starting air valve device.

With chamber 157 vented, the piston 154 in the directional interlock valve device 7 will be in the position in which it is shown in the drawing with the shoe 161 in its retracted position disposed away from the crank shaft 1 assumed to be turning in its "Forward" direction.

With chamber 55 in the starting air valve device 6 vented, it will be appreciated from previous description of operation of said device 6 that starting air supply to the engine will be cut off by the seated valve 64 while the engine starting air pipe 75 will be vented via the unseated valve 69.

Now assume that the operator's lever 200 is moved from its position in slot 201 on the "Forward" side of "Stop" position to "Start" position in slot 211 on the "Reverse" side of "Stop" position, so that consequently the "Forward Control Pipe" 186 will become vented, while the "Reverse Control Pipe" and "Start Control Pipes" 185 and 202 become charged with fluid under pressure.

In response to such change in pressure status in the control pipes 185, 186, engine reversing mechanism (not shown) will effect conditioning of the engine for operation in its reverse direction.

In response to supply of fluid under pressure to the "Reverse Control Pipe" 185, fluid under pressure will flow therefrom by way of the unseated valve 132 in the directional interlock device 7, the pipe 180, shuttle valve 181 and pipe 182 to the chamber 32 to cause movement of stop rod 35 and thereby movement of the fuel control lever 4 to its "Fuel Off" position to terminate supply of fuel to the engine.

Fluid under pressure supplied to the "Start Control Pipe" 202 will flow to chamber 55 in the starting air valve device 6 to cause starting air to be supplied to the engine and, by way of the check valve 10 and pipe 190, such fluid under pressure also will flow to the chamber 157 in the directional interlock device 7 to cause the shoe 161 to be moved into frictional engagement with the rotating crank shaft 1.

Supply of starting air to the engine at this time will act to slow down the engine rotating in its original "Forward" direction until same stops and under normal conditions will then turn the engine over in its new or "Reverse" direction if such supply of starting air is maintained.

As soon as the engine crank shaft 1 starts to turn over in its new or "Reverse" direction, by sidewise movement of the shoe 161 with the shaft 1, the directional interlock device 7 will assume its reverse position seating valve 132 and unseating valve 131, for thereby releasing fluid under pressure from chamber 32 in the fuel cut-off cylinder device 5 by way of the unseated valve 131 and the "Forward Control Pipe" 186 and allowing the fuel control lever 4 to move to a fuel supply position. The engine will then run on fuel in its reverse direction and the interlock shoe 161 then may be retracted through release

5 of fluid under pressure from chamber 157 and termination of supply of starting air effected through release of fluid under pressure from chamber 55 in the starting air control valve device 6. Such release of fluid under pressure will be effected through venting of the start control pipe 202 by movement of operator's lever 200 out of "Start" position into slot 201.

According to the invention, should the start control pipe 202 by prematurely vented to cause termination of starting air supply by movement of operator's lever 200 out of "Start" position into slot 201, that is, vented at a time when the engine has just begun a portion of a revolution 10 in its new or "Reverse" direction sufficient to cause the directional interlock device to assume its reverse position in which fuel cut-off cylinder device chamber 32 is vented via unseated valve 131, the choke 9 will act to so restrict release of 15 fluid under pressure from the chamber 157 in the directional interlock valve device 7 as to maintain the shoe 161 in engagement with the crank shaft 1 for sufficient time as will assure that said interlock device will respond to any 20 "rocking" of the engine back in its original direction to again assume its forward position and effect, through unseating valve 132, resupply of fluid under pressure to the chamber 32 in the fuel cut-off cylinder device 5 to move the fuel 25 control lever 4 to its "Fuel Off" position. It will be seen that under such an operating condition as assumed above, by delaying retraction of the 30 directional interlock shoe 161 away from the shaft 1, the fuel supply to the engine is cut off 35 automatically in case of engine rocking, so that in reversing the engine it is not possible for the engine to start to run on fuel in the wrong or original direction so long as the operator's lever 200 remains in its position to call for reversal 40 of the engine.

With the operator's lever 200 in slot 201 on the forward side of "Stop" position and the "Start Control Pipe" 202 therefore vented, fluid under pressure will continue to release from the chamber 157 in the directional interlock valve 45 device 7 and the shoe 161 will move to its retracted position while said interlock valve device remains in its forward position to hold fuel supply cut off.

To continue starting of the engine in its new 50 or "Reverse" direction, the operator will move the operator's lever 200 back into slot 211 to "Start" position to again cause fluid under pressure to be supplied to the start control pipe 202, whereupon the directional interlock device chamber 157 will 55 again be rapidly charged with fluid under pressure by way of check valve 10 to cause engagement of shoe 161 with shaft 1 while fluid under pressure will also flow to the chamber 55 in the starting air valve device 6 to cause starting air 60 to be supplied to the engine to turn same over in its reverse direction.

The directional interlock valve device 7 will then respond to shift from its forward to its reverse position to release fluid under pressure 65 from the fuel cut-off cylinder device chamber 32 to allow fuel to be supplied to the engine for running same in its reverse direction.

Termination of supply of starting air and retraction of interlock shoe 161 may then be effected in manner as aforescribed by movement 70 of operator's lever 200 out of "Reverse" "Start" position back into slot 201.

It will be appreciated that direction of operation of the engine may be reversed in the opposite direction, that is, from "Reverse" to "For-

ward," in substantially the same manner as above described, by movement of the operator's lever 200 from its position in slot 201 on the "Reverse" side of "Stop" position to the "Forward" "Start" position. It will be seen too, that according to the invention, the choke 9 will function to delay retraction of the interlock shoe 161 to prevent unintentional running of the engine "backwards" should the operator move the lever 200 from "Start" position back into the slot 201 cutting off supply of starting air prematurely at a time when engine "rocking" might occur.

Having now described the invention what I claim as new and desire to secure by Letters Patent, is:

1. In combination with a reversible engine crank shaft rotatable in either of two opposite directions, a fluid pressure conduit, a fluid pressure chamber connected to one end of said conduit, interlock means rendered sensitive to direction of rotation of said crank shaft, upon supply of fluid under pressure to said chamber, to assume a position corresponding to such direction and rendered insensitive upon release of fluid under pressure from said chamber while maintaining such position, choke means in said communication to restrict release of fluid under pressure from said chamber, and check valve means in said communication to allow for facile flow of fluid under pressure to said chamber.

2. The combination as set forth in claim 1, including engine reversing control means having two positions corresponding to the two directions of rotation of said crank shaft and operable while in said positions to effect supply and release of fluid under pressure to and from the opposite end of said conduit.

3. The combination as set forth in claim 2, including engine fuel cut-off means operable to cut off supply of fuel to said engine when position of said interlock means is not in accord with position of said reversing control means.

4. The combination as set forth in claim 3, including engine starting means operable upon supply of fluid under pressure to said opposite end of said conduit to urge the engine to turn over in a direction in accord with position of said engine reversing control means and to terminate said urge upon release of fluid under pressure from said opposite end of said conduit.

5. In combination with a reversible engine crank shaft rotatable in either a forward direction or in a reverse direction, a source of fluid under pressure, a start control pipe, a forward control pipe, a reverse control pipe, a delivery chamber, operator's control means operable to forward positions to effect supply and release of fluid under pressure to and from said start control pipe while maintaining said forward control pipe charged with fluid under pressure and said reverse control pipe vented and operable to reverse positions to effect supply and release of fluid under pressure to and from said start control pipe while maintaining said reverse control pipe charged with fluid under pressure and said forward control pipe vented, valve means movable to a forward position or to a reverse position to establish connection between said delivery chamber and said reverse control pipe or said forward control pipe, respectively, direction sensing means movable by engagement with said shaft when rotating in its forward direction to effect movement of said valve means to its said forward position and when rotating in

its reverse direction to effect movement of said valve means to its said reverse position, a fluid pressure chamber, actuating means responsive to supply and release of fluid under pressure to and from said fluid pressure chamber to effect movement of said direction sensing means into and out of engagement with said shaft, respectively, and choke and check valve means connecting said fluid pressure chamber to said start control pipe for restricting release of fluid under pressure from said fluid pressure chamber and allowing facile flow of fluid under pressure to said fluid pressure chamber.

6. The combination as set forth in claim 5, including engine fuel cut-off means responsive to supply of fluid under pressure to said delivery chamber to effect cut-off of fuel supply to said engine.

7. The combination as set forth in claim 6, including starting air control means responsive to supply of fluid under pressure to said start control pipe to effect supply of starting air to said engine and responsive to release of fluid under pressure from said start control pipe to terminate said supply of starting air.

8. In combination with a directional interlock valve device comprising a fluid pressure chamber and motion sensing means movable into and out of a motion sensing position in response to supply and release of fluid under pressure to and from said fluid pressure chamber, respectively, choke means for restricting release of fluid under pressure from said chamber, and check valve means arranged in by-passing relation to said choke means to allow for facile flow of fluid under pressure to said chamber.

9. Apparatus for controlling supply of fuel to a reversible internal combustion engine having a crankshaft subject to a momentary rocking condition at time of engine reversal, said apparatus comprising fuel control means renderable sensitive to direction of turning movement of said crankshaft to effect supply and cut-off of supply of fuel to said engine according to whether or not said crankshaft is turning in a forward or a reverse direction, respectively, and renderable insensitive to direction of turning movement of said crankshaft to allow fuel to remain in supply or cut-off to said engine according to whichever condition is established at the time said fuel control means is rendered insensitive, operator's control means operable selectively to render said fuel control means either sensitive or insensitive, timing means interposed between said fuel control means and said operator's control means to delay response of said fuel control means to operation of said operator's control means to render said fuel control means insensitive, to allow said fuel control means to remain sensitive for a period of time greater than the time in which said crankshaft rocking condition will exist, and means rendering said timing means ineffective when said fuel control means is being rendered sensitive.

RALPH C. BROOKS.
